UNITED STATES PATENT OFFICE.

ANTHONY G. GILLOTT, OF HALEDON, NEW JERSEY.

HAND-READING DEVICE.

1,404,385.

Specification of Letters Patent. Patented Jan. 24, 1922.

Application filed April 30, 1921. Serial No. 465,690.

To all whom it may concern:

Be it known that I, ANTHONY G. GILLOTT, a citizen of the United States, and a resident of Haledon, in the county of Passaic and State of New Jersey, have invented certain new and useful Improvements in Hand-Reading Devices, of which the following is a specification.

This invention has reference to an apparatus or device to facilitate the reading of hands of various persons; and has for its object to provide means whereby a movable member has various readings or facts at different parts and also index marks at each part, and which member will cause these various parts to be brought to a certain predetermined position such as an opening in a casing; in combination with which the apparatus has a similar movable member with various parts containing the same index marks and adjacent each mark is a reading giving the corresponding characteristics of the person having the part of the hand as set forth in each reading.

25 A further object of the invention is to provide a pair of movable members arranged adjacent to furnish two sets of readings for the hand characteristics; in combination with which a double movable member is provided having two sets of readings thereon corresponding to the said sets of readings on the other member.

35 A further object of the invention is to provide in connection with the casing of such member a kind of chart around the margins illustrating each of the readings on the movable members as shown in the parts of the hand.

40 In the accompanying drawing illustrating one embodiment of my invention, Figure 1 is a plan view.

Fig. 2 is a partial section on the line 2—2 of Fig. 1.

45 As shown in the drawing I provide a casing denoted generally by 1 in which are mounted one or more pairs of movable members having corresponding indications. At one side of the device is mounted a disk 2 with an annular portion 3 exposed at a window or opening 4 in the top of the casing. The margin of this disk is exposed at an opening 5 to be turned by the user by engaging the disk, whereby different portions of the ring 3 are exposed at the window. This can be divided into eight portions that each contain a certain reading

matter, and which portion also contains an index mark, on this disk being lettered from A to H on the disk sections. At this place I provide another disk 6 of smaller 60 diameter that is placed concentric with the said disk and above the same whose edge is inside of the said annular reading portion 3. This disk may be carried by a shaft 7 projecting through the top and provided 65 with a knob 8 to turn the disk. The top of the casing has a window 9 at which this disk will have its annular portion 10 exposed. The disk 10 is divided into four sections or parts each of which will be entirely exposed at the window 10, when turned. These sections will each contain certain reading matter and also each section is given an index mark such as letters 70 J, K, L and M.

To operate in conjunction with the disk 2, I provide a disk 12 similarly mounted to rotate to expose an annular portion 13 at a window 14 in the casing and this disk has its edge exposed at an opening 15 in the 80 casing to be turned by the user. The annular portion 13 is divided into eight sections and each is lettered from A to H corresponding to the disk 2. Each of these sections contains reading matter giving the character of the person whose features of the hand are set forth in the said sections of disk 2.

In a similar manner, the disk 13 may have adjacent thereto and concentric therewith a 90 disk 16 supported by a shaft 17 that is turned by a knob 18 on top of the casing. The disk 16 has an annular portion 19 that may be divided into four sections arranged to be brought successively to view at a window 20 in the top of the casing. These four sections are lettered J, K, L and M and correspond to the sections of the disk 6. These sections contain reading matter giving characteristics of the person whose hand on certain parts has indications as set forth in the reading matter in the sections on the disk 16.

These two disks may be duplicated by another pair of double disks, provided in the casing. As shown the disk 21 has six sections with index marks N, O, P, Q, R and S, and reading matter in each section; which sections are exposed at a window 22 in the casing, adjacent an opening 23 to engage the edge of this disk for its rotation. Concentric with this disk 21 is a similar disk 24 turned by a knob 25 to bring four sections

for view at a window 26 in the casing. These sections are lettered R, U, V and W, and contain reading matter giving certain indications on the hand.

- 5 A similar pair of disks is provided to cooperate with the latter disks. As shown I provide a disk 30 having six sections lettered from N to T brought for exposure to a window 31 in the casing. Each of these sections 10 has reading matter giving the characteristics of the person corresponding to the indications in the similar lettered part on the disk 21. The disk 30 is exposed at an opening 32 in the casing to engage this edge for rotation. 15 A smaller disk 33 is mounted concentric with the disk 31 and turned by a knob 34 to bring four sections of an annular portion thereof to register with a window 35 in the casing. These four sections are lettered T, U, V and 20 W, and each contains reading matter giving the characteristics of the person corresponding with the indications in the similar sections on the disk 24.

On one face of the casing, preferably at 25 the margin, are provided small portions bearing pictures of the hand, and are lettered similar to the twenty-two sections on the four disks and lettered accordingly. As set forth in the drawing the disk 2 contains 30 in its eight sections the particular form of the mounts on the hand. These mounts are portions of the palm. On the disk 12 that has the eight sections lettered similar to the disk 2, the reading matter indicates the form 35 of character of the person whose hand mount is set forth in the disk 2.

The smaller disk 6 contains in these four sections reading matter descriptive of the finger; and the corresponding disk 20 contains 40 reading matter having the same letters as on the disk 6, and this reading matter sets forth the mental inclination of the person whose fingers correspond with some one of the four descriptions on the disk 6. The disk 21 as set forth contains these sections with reading matter descriptive of the thumb; and the corresponding disk 30 that has the same letters on its sections, has reading 45 matter setting forth the character of the will power of the person whose thumb corresponds with some one of the readings on the disk 21. The fourth disk 24 contains sections with descriptions of the tips of the fingers or the finger end portions; and the disk 50 33 that contains the same index marks or letters and has readings denoting the temperament of the person whose finger tips correspond with one of the descriptions set forth on the disk 24. In the use of the device, the 55 hand of the person is read and the four disks 2, 6, 21 and 24 are turned to bring the sections to view corresponding with such hand. Thereupon the disk 12 is turned to bring the index to correspond with that on the disk 2; 60 the disk 20 to correspond with the disk 10;

the disk 30 to correspond with the disk 21, and the disk 22 to correspond with the disk 24, which will give the proper readings for such hand. In the use of the device the hand is compared with the illustrations shown in 70 the several lettered sections on the margin of the casing.

What I claim is:

1. In a device of the character set forth, the combination of a casing having four 75 openings in one face, a rotary member arranged to turn in the casing to have a concentric annular portion thereof exposed at one of said openings as the member is turned, said annular portion having at different parts reading matter that is successively visible at said openings as the member is turned, each said reading matter having an index mark also visible, a second rotary member in the casing having a concentric annular portion exposed at another opening as the member is turned, the latter member having index marks at successive parts of the annular portions that are the same as said index 80 marks, the latter member also having reading matter adjacent each said index mark having a predetermined relation with the reading matter of the same index on the other rotary member, a third rotary member arranged to turn concentric with said first 85 rotary member and having a concentric annular portion exposed at a third opening in the casing, said latter member having sets of reading matter with an index mark at successive parts of the annular portion to be 90 exposed at said opening, a fourth rotary member arranged to turn concentric with said first 95 rotary member and having a concentric annular portion exposed at a fourth opening in the 100 casing, said latter annular portion having index marks exposed at said openings that are the same as the index marks on the third 105 annular member, said fourth annular member also having reading matter adjacent 110 these said index marks having predetermined relations to the reading matter on the third rotary member.

2. In a device of the character set forth, the combination of a casing having openings 115 in one face, a rotary member arranged to turn in the casing to have a concentric annular portion thereof exposed at one of said openings as the member is turned, said annular portion having at different parts reading 120 matter to indicate palm mounts, that is successively visible at said openings as the member is turned, each said reading matter having an index mark also visible, a second rotary member in the casing having a concentric 125 annular portion exposed at another opening as the member is turned, the latter member having index marks at successive parts of the annular portions that are the same as said index marks, the latter member also 130

having reading matter adjacent each said index mark which is character description indicated by said mounts respectively.

3. In a device of the character set forth, 5 the combination of a casing having openings in one face, a rotary member arranged to turn in the casing to have a concentric annular portion thereof exposed at one of said openings as the member is turned, said annular portion having at different parts reading matter descriptive of the fingers that is successively visible at said openings as the member is turned each said reading matter having an index mark also visible, a second 10 rotary member in the casing having a concentric annular portion exposed at another opening as the member is turned, the latter member having index marks at successive parts of the annular portions that are the same as said index marks, the latter member also having reading matter adjacent each said index mark giving mental inclinations corresponding to the finger characteristics.

4. In a device of the character set forth, 25 the combination of a casing having openings in one face, a rotary member arranged to turn in the casing to have a concentric annular portion thereof exposed at one of said openings as the member is turned, said annular portion having at different parts reading matter giving characteristics of the thumb that is successively visible at said openings as the member is turned, each said reading matter having an index mark also visible, a second 30 rotary member in the casing having a concentric annular portion exposed at another opening as the member is turned, the latter member having index marks at successive parts of the annular portions that are the same as said index marks, the latter member also having reading matter adjacent each said index mark giving will power characteristics corresponding to the thumb indications.

45 5. In a device of the character set forth, the combination of a casing having openings in one face, a rotary member arranged to turn in the casing to have a concentric annular portion thereof exposed at one of said openings as the member is turned, said annular portion having at different parts reading matter giving characteristics of the finger tips that is successively visible at said openings as the member is turned, each said reading matter having an index mark also visible, a second rotary member in the casing having a concentric annular portion exposed at another opening as the member is turned, the latter member having index marks at 50 successive parts of the annular portions that are the same as said index marks, the latter member also having reading matter adjacent each said index mark showing the temperamental characteristics.

60 6. In a device of the character set forth,

the combination of a casing having openings in one face, a rotary member arranged to turn in the casing to have a concentric annular portion thereof exposed at one of said openings as the member is turned, said annular portion having at different parts reading matter that is successively visible at said openings as the member is turned, each said reading matter having an index mark also visible, a second rotary member in the casing 70 having a concentric annular portion exposed at another opening as the member is turned, the latter member having index marks at successive parts of the annular portions that are the same as said index marks, the latter member also having reading matter adjacent each said index mark having predetermined relation with the reading matter of the same index on the other rotary member, the casing having a series of hand illustrations corresponding to the descriptions on the first rotary member.

7. In a device of the character set forth, the combination of a casing having four openings in one face, a rotary member arranged to turn in the casing to have a concentric annular portion thereof exposed at one of said openings as the member is turned, said annular portion having at different parts reading matter that is successively visible at said openings as the member is turned, each said reading matter having an index mark also visible, a second rotary member in the casing having a concentric annular portion exposed at another opening as the member is turned, the latter member having index marks at successive parts of the annular portions that are the same as said index marks, the latter member also having reading matter adjacent each said index mark having a predetermined relation with the reading matter of the same index on the other rotary member, a third rotary member arranged to turn concentric with said first rotary member and having a concentric annular portion exposed at a third opening in the casing, said latter member having sets of reading matter with an index mark at successive parts of the annular portion to be exposed at said opening, a fourth rotary member arranged to turn concentric with said rotary member, the fourth rotary member having a concentric annular portion exposed at a fourth opening in the casing, said latter annular portion having index marks 110 exposed at said openings that are the same as the index marks on the third annular member, said fourth annular member also having reading matter adjacent these said index marks having predetermined relations to 115 the reading matter on the third rotary member, the casing having a series of hand illustrations corresponding to the descriptions on the first and third rotary member.

8. In a device of the character set forth,

the combination of a casing having four openings in one face, a rotary member arranged to turn in the casing to have a concentric annular portion thereof exposed at 5 one of said openings as the member is turned, said annular portion having at different parts reading matter descriptive of the hand that is successively visible at said openings as the member is turned, each said reading 10 matter having an index mark also visible, a second rotary member in the casing having a concentric annular portion exposed at another opening as the member is turned, the latter member having index marks at successive 15 parts of the annular portions that are the same as said index marks, the latter member also having reading matter adjacent each said index mark descriptive of the person, a third rotary member arranged to turn 20 concentric with said first rotary member

and having a concentric annular portion exposed at a third opening in the casing, said latter member having sets of reading matter descriptive of the hand with an index mark at successive parts of the annular portion to be exposed at said opening, a fourth 25 rotary member arranged to turn concentric with said second rotary member, the fourth rotary member having a concentric annular portion exposed at a fourth opening in the 30 casing, said latter annular portion having index marks exposed at said openings that are the same as the index marks on the third annular member, said fourth annular member also having reading matter adjacent 35 these said index marks descriptive of the person.

Signed at New York city, N. Y., on April 28th, 1921.

ANTHONY G. GILLOTT.
